ORNAMENTAL COLUMN

Herman Sabel, Leon W. Sabel, and Arnold Sabel, all of
Rte. 1, Box 233, Folley Road, Charleston, S.C.

Filed May 4, 1961, Ser. No. 65,027

Term of patent 3½ years

(Cl. D54—2)

FIG. 1 is a front elevational view of an ornamental column showing our new design;

FIG. 2 is a sectional view taken along the plane of section line 2—2 of FIG. 1 illustrating the rear surface of the ornamental column; and

FIG. 3 is an enlarged view of a portion of the grillwork shown in FIG. 1 showing the details thereof.

The rear surface of the grillwork is intaglio with the front surface.

We claim:

The ornamental design for an ornamental column, as shown and described.
